UNITED STATES PATENT OFFICE.

JOHN RICHARD BARKER, OF JACKSONVILLE, FLORIDA.

EJECTOR.

1,116,971.

Specification of Letters Patent.

Patented Nov. 10, 1914.

Application filed November 14, 1913. Serial No. 800,969.

To all whom it may concern:

Be it known that I, JOHN R. BARKER, a citizen of the United States, and a resident of Jacksonville, in the county of Duval and 5 State of Florida, have invented a new and Improved Ejector, of which the following is a full, clear, and exact description.

This invention relates to dredging or excavating machinery and has particular reference to certain specific improvements in 10 hydraulic dredges or dredges which depend for their operation upon the injector action of a current of water, air, steam or the like under pressure and discharged through a contracted opening.

Among the objects of the invention is to simplify and improve this sort of devices whereby the force of the propelling stream is better availed of for the dredging and 20 discharging actions than heretofore.

The foregoing and other objects of the invention will hereinafter be more fully described and claimed and illustrated in the drawings forming a part of this specification 25 in which like characters of reference indicate corresponding parts in all the views, and in which—

Figure 1 is a longitudinal section through the principal parts of this invention; Fig. 2 30 is a transverse section on the line 2—2 of Fig. 1; and Fig. 3 is a detail of a part of the nozzle mechanism shown in Fig. 1.

The several parts of the device may be made of any suitable materials, and the relative sizes and proportions, as well as the general design of the mechanism, may be varied to a considerable extent without departing from the spirit of the invention hereinafter more fully set forth and specifically claimed.

A device made in accordance with this invention includes a base 10 having a cylindrical central portion of a size and form conforming to the main discharge pipe and 45 having a flange 11 adapting it to be connected to a suction pipe 12 as by means of clamping bolts. At the other end of the barrel portion of the base is formed integrally a substantially disk-shaped flange 13 of comparatively wide expanse and this flange is provided with a plurality of openings 13' having their axes parallel to the axis of the base or the direction of movement of the material being dredged.

At 14 I show a substantially drum-like

member constituting, together with the other parts to which it is attached, a pressure chamber. This shell 14 is largest at its lower or receiving end and tapers somewhat toward its upper end. Said lower end is 60 secured rigidly to the outer edge of the base flange 13.

The numeral 15 indicates a nozzle registering with and constituting a continuation of the cylindrical part of the base and is 65 rigidly secured to the flange 13 thereof by means of a flange 16 and clamping bolts extending through both flanges. The proper alinement of these members is determined and maintained also by means of a rabbeted 70 connection at 16'. The discharge end of the nozzle is rounded and tapered on the outside, as shown at 15', the extreme end, however, of the tapered portion being conical in form as shown at 15".

At 17 I show a head constituting another portion of the nozzle mechanism. This member has a mouth 18 closely associated with the discharge end of the nozzle and having an inner wall constituting a counterpart of the tapered portion of the nozzle above described and including a rounded surface 18' and a conical surface 18''. Said mouth also includes a slight ledge 19 opposite the extreme end of the nozzle formed by 80 an enlargement of the receiving end of the mouth, the mouth portion beyond the nozzle being slightly contracted toward its discharge end and having substantially the same diameter as the bore of the nozzle. 90 The head 17 is secured in place with respect to the shell or drum 14 by means of a flange 17' bolted to a flange 14' at the discharge end of the drum. The intermediate portion of the head, as shown at 17^a, is provided with a curved swell or enlargement 95 surrounding the discharge end of the mouth 18.

A discharge pipe is shown at 20 and is connected in any suitable manner to the discharge end of the head 17. The discharge pipe is preferably provided on its inner surface with a series of substantially parallel spirally arranged ribs 21 of a long pitch, the purpose of the ribs being to cause the 100 material being discharged to be rotated around the center axis of the discharge mechanism and hence prevented from settling at the bottom of any of the parts.

From the description above given it will 110

be understood that the narrow contracted space between the discharge end of the nozzle 15 and the mouth of the head, or more definitely, between the conical surfaces 15" and 18", is of a conical form, the slanting of the cone being such as to produce substantially an angle of 60 degrees at or near the discharge end of the head, as shown by the dotted lines in Fig. 1. A pressure fluid is 10 adapted to be delivered into and through the pressure chamber or drum 14 by means of delivery pipes 22 secured in the aforesaid openings 13' of the base flange 13 and such fluid is delivered under a high pressure 15 from the opposite end of the drum and in a substantially direct line from the delivery pipes 22 into the head 17. The stream of such fluid being delivered through the conical opening tends to condense at the apex 20 of the cone as indicated at 23, and hence forms a substantial closure for the discharge pipe 20. Such stream, however, passing onward under force causes a vacuum to be formed in or through the base and nozzle 25 with the result that sand, mud or other loose earth being excavated will be drawn into and through the nozzle and thence into and through the discharge pipe.

Among the purposes or advantages for 30 the offset indicated at 19 is to allow the water or other propelling medium to leave the end of the jet 15 perfectly square and not to drag along the sides of the casting. Among the advantages also of the outward 35 swell 17^a of the head is that in forcing water or other propelling fluid through the jet at high pressure, there is a tendency for an eddy to be formed, the retarding effect of which is overcome by such outward 40 curve or swell. In addition to the employment of this device for excavating purposes, it is obvious that the features of novelty covered thereby are applicable for use in connection with vacuum cleaners for 45 household use, for instance, or for conveyers of other dry granular or pulverulent materials.

Having thus described my invention, I

claim as new and desire to secure by Letters Patent:—

50

1. In a device of the character set forth, the combination of a base having a disk-like flange, a nozzle secured to said flange, in coaxial alinement with the base, a drum surrounding the nozzle and secured to the outer edge of the base flange, means to introduce pressure fluid into the space between the drum shell and the nozzle through said base flange, a head secured to the outer end of the drum and having a portion in close spaced relation to the end of the nozzle forming a conical discharge opening for the pressure fluid, the head being formed adjacent the end of the nozzle with an offset 19 surrounding the fluid space, and a discharge 65 pipe connected to the delivery end of the head.

2. In a device of the character set forth, the combination of a base having a cylindrical barrel portion and an outwardly projecting disk-like flange, a cylindrical nozzle conforming in size and having rabbeted engagement in alinement with said base, means to secure the nozzle to said base flange, a drum surrounding the nozzle and 75 having connection to the outer edge of said disk-like flange, said drum forming with the nozzle a pressure chamber, and a head secured to the drum, the adjacent surfaces of the nozzle and head forming a thin 80 hollow conical discharge space for the pressure fluid from the pressure chamber, the mouth of the head just beyond the nozzle being slightly enlarged forming a ledge opposite the edge of the nozzle, and that 85 portion of the head beyond the mouth being enlarged at 17^a forming a high pressure chamber, substantially as and for the purposes set forth.

In testimony whereof I have signed my 90 name to this specification in the presence of two subscribing witnesses.

JOHN RICHARD BARKER.
